CIGARETTE MAKING MACHINE

Ming Gee, Boston, Mass.

Application December 7, 1951, Serial No. 260,374

2 Claims. (Cl. 131—70)

This invention relates to cigarette making machines, and more particularly to a machine arranged to pack tobacco into a tubular paper cylindrical container to form a cigarette.

A main object of the invention is to provide a novel and improved cigarette making machine which is simple in construction, which is easy to operate, and which is very compact in size.

A further object of the invention is to provide an improved cigarette making machine which is relatively inexpensive to manufacture, which is durable in construction, which is reliable in operation, and which involves a simple manual operation to form a cigarette.

Further objects and advantages of the invention will become apparent from the following description and claims, and from the accompanying drawings, wherein:

Figure 1 is a top plan view of an improved cigarette making machine according to the present invention shown set up for use with the operating handle thereof in its initial position.

Figure 2 is a top plan view of the machine of Figure 1 showing the operating handle in an intermediate position of its operating stroke.

Figure 3 is a top plan view of the machine of Figure 1 showing the operating handle at the final position of its operating stroke.

Figure 4 is a bottom plan view of the machine with the operating handle in the position of Figure 1.

Figure 5 is a bottom plan view of the machine of Figure 1 with the operating handle in the position of Figure 2.

Figure 6 is a bottom plan view of the machine of Figure 1 with the operating handle in the position of Figure 3.

Figure 7 is an enlarged transverse vertical cross sectional view taken on the line 7—7 of Figure 1.

Figure 8 is an enlarged transverse vertical cross sectional view taken on the line 8—8 of Figure 2.

Figure 9 is an enlarged vertical longitudinal cross sectional view taken on the line 9—9 of Figure 1.

Figure 10 is an enlarged longitudinal vertical cross sectional view taken on the line 10—10 of Figure 3.

Figure 11 is a front end elevational view of the machine of Figure 1 with the tobacco receiving hopper removed.

Figure 12 is a front end elevational view of the machine of Figure 1 with the operating handle at the end of its operating stroke, as in Figure 3.

Figure 13 is an enlarged cross sectional detail view taken on the line 13—13 of Figure 12 and showing the tobacco-receiving hopper mounted in its guides, the tobacco-receiving hopper being shown in folded position.

Figure 14 is a perspective detail view of the cigarette ejecting plunger employed in the machine of Figure 1.

Referring to the drawings, the cigarette making machine is designated generally at 20 and comprises a supporting housing of rectangular shape shown at 21, having the base flanges 22 extending around its perimeter. Secured to the margin of the base flange 22 at the forward

2

side of the housing are the respective depending C-shaped brackets 23, 23 provided with the clamping screws 24 extending vertically through their lower arms, whereby the device may be clamped to the margin 25 of a table 26 in the manner shown in Figures 11 and 12.

The rectangular main body portion of the housing 21 includes the horizontal top plate 27, defining the top wall of said housing. The housing 21 is formed adjacent a forward corner thereof, for example, adjacent the left forward corner, as viewed in Figure 1, with an elongated rectangular slot 28 arranged parallel to the forward longitudinal margin of the housing. Secured to the plate 27 adjacent the slot 28 are the transversely extending parallel inwardly flanged guides 29, 29 between which a foldable tobacco receptacle, shown at 30, is adapted to be slidably received, the guides 29, 29 being arranged to receive the edges of a bottom plate 31 provided on the foldable receptacle 30. As shown in Figures 1 and 2, the guides 29, 29 are arranged to receive the tobacco receptacle 30 in a position wherein the forward end of the receptacle is disposed adjacent the slot 28, said forward end being open, whereby tobacco in the receptacle may be readily moved into the slot 28.

Designated at 32 is an operating handle which is secured to the top end of a vertical shaft 33 rotatably mounted in the intermediate portion of the plate member 27. As shown in Figure 9, the shaft 33 extends upwardly through a shouldered washer 34, a rectangular plate 35, and the channel-shaped handle 32 and into threaded engagement with a cap nut 36. The rectangular plate member 35 is formed with a slot which engages on the top end of the shaft 33. The plate member 35 fits snugly within the channel-shaped handle 32, as shown in Figure 9, and the slot in the intermediate portion of said plate member engages opposed parallel flattened portions 37, 37 on opposite sides of the upper portion of shaft 33, whereby the plate member 35 is non-rotatably locked with respect to the shaft. A coiled spring 38 surrounds the shaft bearing between the washer 34 and the plate member 35, biasing the handle 32 upwardly and urging the plate member 35 against the web of said handle.

Secured to the shaft 33 beneath the plate member 27 is the cam 39. Rotatably mounted on the shaft 33 and overlying the cam 39 is an arm 40. Secured on the cam 39 and projecting upwardly therefrom is a pin 41 which is arranged to engage the arm 40 after the cam 39 has been rotated in a counterclockwise direction, as viewed in Figure 4, to an angle of approximately 120° from the position shown in Figure 4. The arm 40 is biased clockwise, as viewed in Figure 4, by a coiled spring 42 connecting the arm and the left end wall of the housing 21, as viewed in Figure 4.

Designated at 43 is a receiving plate secured below and parallel to the top plate member 27 beneath the slot 28, as shown in Figure 7, said plate 43 being formed with an upstanding flange 44 extending substantially into abutment with the under side of the top plate 27 and spaced laterally from one edge of the slot 28 to define a tobacco receiving cavity beneath slot 28 and the adjacent portion of plate 27. Designated at 45 is a substantially rectangular compressor block which is slidably mounted on the receiving plate 43, said block being formed with a groove 46 in its longitudinal edge opposing the flange 44. Pivoted at 47, 47 to the underside top plate 27 are respective link bars 48, 48, and pivoted to the longitudinal marginal portion of the compressor block 45 at 49, 49 are additional link arms 50, 50. Each pair of link arms 48 and 50 is pivotally connected at 51 to a longitudinally extending arm 52 which is provided at its end with a follower element 53 extending through an arcuate cam slot 54 formed in the cam 39. The

linkage defined by the link arms 48, 50 and 52 is arranged to reciprocate the compressor block 45 transversely with respect to the top plate 27 responsive to the rotation of the handle 32 by the cooperation of the follower 53 with the arcuate cam slot 54. The block 45 is thus moved from a position retracted rearwardly past the slot 28, which is the starting position, to a position adjacent the flange 44, shown in Figure 8, responsive to counterclockwise rotation, as viewed in Figure 4, of the handle 32 to an angle of approximately 120°. It will be noted that in the starting position, namely the position shown in Figure 7, the slot 28 communicates with the tobacco-receiving cavity, whereas in the advanced position of the compressor block 45, shown in Figure 8, the block 45 has moved forwardly past the slot 28 and is effective to compress tobacco into a substantially cylindrical shape, in cooperation with the flange 44. It will be further noted, from Figure 5, that the arm 52 is moved somewhat past the dead center position of the link arms 48 and 50 to the right, as viewed in Figure 5, whereby the block 45 is retracted slightly as the cam 39 is rotated to the position of Figure 5. Therefore, the compression of the tobacco is slightly relieved as the handle 32 reaches the end of this initial portion of its operating stroke.

Designated at 55 is a short conduit member secured in the end wall of the housing 21 in alignment with the cavity defined between the grooved edge of block 45 and the flange 44 when the block 45 is in the position thereof shown in Figure 8. The conduit 55 is adapted to receive a paper cigarette tube 56 telescoped thereon, into which the tobacco compressed in the cavity is injected, as will be presently described. Designated at 57 is a hollow elongated guide sleeve rigidly secured beneath the top plate 27 in alignment with the tube 55 on the opposite side of the cavity defined between flange 44 and the groove 46, above mentioned. Slidably mounted in the sleeve 57 is a plunger 58. The sleeve 57 is formed with an elongated longitudinal slot 59. Connected to the plunger 58 by a pin 60 extending through slot 59 is a link arm 61. The link arm 61 is pivotally connected at 62 to the end of arm 40. The plunger 58 is formed at its left end, as viewed in Figure 9 with a reduced, thin channeled extension 63 which is normally disposed adjacent to the flange 44, as shown in Figure 7, said channeled extension opposing the groove 46, as is clearly shown in Figure 7.

As the cam 39 is rotated by the handle 32, in a counterclockwise direction, as viewed in Figure 4, and as above explained, the pin 41 engages the arm 40 at the end of the initial portion of the rotation stroke of arm 32, of approximately 120° counterclockwise, and the pin 41 then acts against the arm 40, causing the arm 40 to be rotated counterclockwise, whereby the plunger 58 is moved toward and through the cavity defined between the grooved end of the block 45 and flange 44. The cam 39 is formed with a continuation 64 of the slot 54, the slot portion 64 being arcuate in shape and having its center at the axis of shaft 33, whereby it causes no motion of the follower 53 as the operating handle 32 is rotated to the concluding portion of its stroke.

It will be apparent that the plunger 58 causes the compressed tobacco in the cavity between the block 45 and flange 44 to be injected through the conduit 55 into the cigarette tube 56 responsive to the rotation of the operating handle 32 through the second portion of its stroke, namely through that portion subsequent to the engagement of the pin 41 with the arm 40.

Pivoted at 65 to the bottom surface of the receiving plate 43 is a lever 66 having one arm thereof, shown at 67, projecting through a slot in the end wall of the housing 21 to a position adjacent the conduit 55. Sealed to the end of the arm 67 is a vertical pin 68 on which is mounted a roller 69. A coiled spring 70 con-

ncts the arm 67 to the adjacent front longitudinal wall of the housing 21 and biases the roller 69 toward engagement with the conduit 55. The lever 66 has an arcuate extension 72 which extends over and adjacent to the arm 40. The arm 40 has secured thereto an upwardly extending pin 73 which is engageable with the inner edge of the extension 72, as shown in Figure 5. The extension 72 is biased into engagement with the pin 73 by the action of the spring 70. Said extension 72 is formed with a shouldered portion 74 which is arranged to engage pin 73 so as to normally maintain the roller member 69 spaced slightly from the conduit 55. During the rotation of the arm 40, as the pin 73 leaves the shouldered portion 74, the lever 66 is released and the roller member 69 comes into clamping engagement with the conduit 55. Therefore, a cigarette tube 56 may be freely engaged on the conduit 55 without interference from the roller 69 when the device is in its normal position, shown in Figure 1. However, shortly after the operating handle 32 concludes the initial portion of its stroke, namely, the portion in which the tobacco is compressed in the tobacco-receiving cavity, the clamping roller 69 is forced against the end of the cigarette tube, holding said tube on the conduit 55 during the injection of the tobacco into the tube by the plunger 58, as above described.

Adjustably secured on the lever 66 by the screw 71 is the slotted adjustable cam element 75 which is arranged to be engaged by the pin 73 at the end of the operating stroke of the handle 32. When the pin 73 engages the rising portion 76 of the cam element 75, the lever 66 is rotated counterclockwise, as viewed in Figure 5, and as shown in Figure 6, causing the clamping roller 69 to be moved away from the conduit 55 and releasing the cigarette tube 56, whereby the completed cigarette may be removed from the conduit member 55.

It will be readily apparent that in operation of the device, it is merely necessary to mount a cigarette tube 56 on the conduit member 55, move the required amount of tobacco through the slot 28 onto the receiving plate 43, and then to rotate the handle 32 clockwise from the position thereof shown in Figure 1 to the position thereof shown in Figure 3. The tobacco is compressed during the first portion of the stroke of the handle 32, namely, through approximately 120° of clockwise rotation thereof, as viewed in Figure 1, and the compressed tobacco is then injected into the cigarette tube by the action of the plunger 58 during the remainder of the rotational stroke of the handle. The cigarette tube is clamped to the conduit 55 during the time that the plunger 58 is injecting the tobacco into the tube, and the cigarette tube is released at the conclusion of the injection stroke of said plunger by the engagement of the pin 73 with the release cam 75, as above described. The parts return to their normal positions when the operating handle 32 is returned to the starting position thereof shown in Figure 1.

The tobacco container 30 may be of any suitable construction, such as of a foldable construction having the inwardly foldable side walls 77, 77 and the inwardly foldable rear end wall 78, the side walls 77, 77 being foldable over the end wall 78 when the container is in its collapsed or folded position. Figure 13 shows said container in the folded position thereof.

While a specific embodiment of an improved cigarette making machine has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A cigarette making machine comprising a support, a horizontal top plate mounted on said support, said plate being formed with an aperture adapted to receive tobacco, a foldable tobacco container mounted on said top plate,

said container having an open end disposed adjacent said aperture, whereby tobacco may be fed through said open end into said aperture, a conduit member adapted to receive a paper cigarette tube telescoped thereon, and means secured beneath said top plate in alignment with said aperture for forming and ejecting tobacco through said conduit member.

2. A cigarette making machine comprising a support, a horizontal top plate mounted on said support, said plate being formed with an aperture adapted to receive 10 tobacco, a container slidably mounted on said top plate, said container comprising a base member engaging said top plate, said base member having an edge thereof adjacent said aperture and upstanding side walls respectively hingedly secured to the remaining edges of said 15 base member, whereby said side walls may be folded inwardly and downwardly to a position overlying said base member, a conduit member secured to said support

for receiving a cigarette paper thereon, and means secured beneath said top plate in alignment with said aperture for compressing and ejecting tobacco from said cavity through said conduit member.
